Primary Examiner—Brian N Vinson(74) *Attorney, Agent, or Firm*—Cislo & Thomas, LLP(57) **CLAIM**

The ornamental design for an air cooling device, as shown and described.

DESCRIPTION

FIG. 1 is a front perspective view of the air cooling device; FIG. 2 is a front elevation view thereof;

FIG. 3 is a top plan view thereof;

FIG. 4 is a right side elevation view of the air cooling device with the left side being a mirror image thereof;

FIG. 5 is a bottom plan view thereof; and,

FIG. 6 is a rear elevation view thereof.

The broken lines showing environment in the drawings are for illustrative purposes only and form no part of the claimed design.
